UNITED STATES PATENT OFFICE.

ALTHIA A. MEEKER, OF ELDON, IOWA.

DESIGN FOR A PLATE.

58,248.

Specification for Design.

Patented June 28, 1921.

Application filed January 20, 1921. Serial No. 438,749. Term of patent 7 years.

To all whom it may concern:

Be it known that I, ALTHIA A. MEEKER, a citizen of the United States of America, residing at Eldon, in the county of Wapello and State of Iowa, have invented a new, original, and ornamental Design for Plates, reference being had to the accompanying drawing, forming part thereof.

Figs. 2 and 3 are sections taken respectively on the lines 2—2 and 3—3 of Fig. 1.

I claim:—

The ornamental design for a plate as shown.

In testimony whereof I affix my signature.

ALTHIA A. MEEKER.
